(57) **CLAIM**

The ornamental design for a stand for portable electronic device, as shown and described.

DESCRIPTION

FIG. 1 is a front perspective view of a stand for portable electronic device showing my new design.

FIG. 2 is a rear perspective view thereof.

FIG. 3 is a front elevational view thereof.

FIG. 4 is a rear elevational view thereof.

FIG. 5 is a left elevational view thereof.

FIG. 6 is a right elevational view thereof.

FIG. 7 is a top plan view thereof; and,

FIG. 8 is a bottom plan view thereof.

The broken lines in the drawing figures depict portions of the stand for portable electronic device that form no part of the claimed design.

1 Claim, 7 Drawing Sheets
